United States Patent

Des. 237,284
Patented Oct. 21, 1975

237,284

COMBINED TABLE AND AQUARIUM

Wayne E. Mertz, 4207 Gerard Ave. N.,
Minneapolis, Minn. 55412

Filed Dec. 6, 1973, Ser. No. 422,363

Term of patent 7 years

Int. Cl. D30—02

U.S. Cl. D30—9

FIG. 2

FIG. 1

FIG. 1 is an elevational view of one of the identically appearing sides of a combined table and aquarium showing my new design.

FIG. 2 is a top plan view thereof.

I claim:

The ornamental design for a combined table and aquarium, as shown and described.
